UNITED STATES PATENT OFFICE.

FREDERIK CHRISTIAN CARL VINCENT NÆSER AND NIELS AUGUST JOHANNES
LILLIENDAHL-PETERSEN, OF COPENHAGEN, DENMARK.

TELEPHONE.

1,243,755.

Specification of Letters Patent. Patented Oct. 23, 1917.

Application filed February 7, 1917. Serial No. 147,104.

To all whom it may concern:

Be it known that we, (1) FREDERIK CHRISTIAN CARL VINCENT NÆSER and (2) NIELS AUGUST JOHANNES LILLIENDAHL-PETERSEN, citizens of the Kingdom of Denmark, residing at (1) No. 81 Sortedamsdossering, (2) No. 114 Blegdamsvej, both in Copenhagen, in the Kingdom of Denmark, have invented certain new and useful Improvements in Telephones, of which the following is a specification.

Our invention, which refers to auxiliary apparatus for telephones, microphones, and the like, is based upon the experience that a telephone membrane causes essentially plainer and stronger sound waves if, instead of immediately affecting the air, it is connected with the membrane in a sounding-box and is heard through its suitably large trumpet. Consequently the invention consists in the combination of a sounding-box, supplied with a trumpet, the membrane of which has a contact member for a telephone membrane, and an underlay for conveniently disposing a telephone, a microphone, or the like, as well as members which insure an adjustable contact between the contact member of the sounding-box membrane and the telephone membrane.

The drawing shows an outline sketch of one form of construction, by way of example.

The sounding-box or "tambour" 1, is, by means of a strap 2, movably suspended on a standard 3. The sound-trumpet 4 rests in a fork 5, whose screw-threaded rod 6 can be adjusted by means of a nut 7 in relation to another standard 8. In this way a height-adjustment can be given to the head 9 on a pin, which, by means of spider legs 10, is connected with the membrane 11 of the sounding-box. On a resilient underlay 12 on the foot-plate 13 there is disposed a bearing-piece 14, in which a micro-telephone can be conveniently placed in such a position that the telephone 15 comes under the sounding-box 1 with the contact member 9 of its membrane in contact with the telephone membrane 16. If the resilient underlay is properly adjusted, the speech can be heard very plain and strong through the trumpet 4, all disturbing sub-tones and by-tones being eliminated by the transmission of the

sound-waves through the sounding-box. The speech can be heard at a distance from the apparatus, and thus can be heard by several persons at once. The hearer or hearers can speak into the microphone 17 in the usual manner, the trumpet of the microphone being eventually turned into the position 170.

The shown details are, both with respect to the correlative situation of the bearing-piece and the frame of the sounding-box and their form, and with respect to the underlay and its adjustment, without significance to the invention, and can be modified in many different ways.

We claim—

1. The combination of a telephone, a sounding box having a membrane provided with a projecting contact adapted to engage the membrane of said telephone, a resilient support for said telephone, and a movable support for said sound box. 75

2. The combination of a telephone, a sounding box having a membrane provided with a spider frame carrying a projecting contact adapted to engage the membrane of said telephone, a resilient support for 80 said telephone, and a movable support for said sound box.

3. The combination of a telephone, a sounding box having a membrane provided with a projecting contact adapted to engage the membrane of said telephone, a resilient support for said telephone, a movable support for said sound box, and a trumpet 85 attached to said sound box.

4. The combination of a telephone, a sounding box having a membrane provided with a projecting contact adapted to engage the membrane of said telephone, a resilient support for said telephone, a movable support for said sound box, a trumpet attached to said sound box, a supplemental support for said trumpet, and means for adjusting said supplemental support to regulate said contact with relation to said telephone membrane. 95

In testimony whereof we affix our signatures.

FREDERIK CHRISTIAN
CARL VINCENT NÆSER.
NIELS AUGUST JOHANNES
LILLIENDAHL-PETERSEN.
